CLAIM

The ornamental design for an image transmitter, as shown and described.

DESCRIPTION

FIG. 1 is a top, front and side perspective view of an image transmitter showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view thereof from the left of FIG. 2;

FIG. 7 is a side elevational view thereof from the right of FIG. 2;

FIG. 8 is a view similar to FIG. 1 with the parts in a different position; and,

FIG. 9 is a top, front and side perspective view thereof, with the lens portion shown in broken line for illustrative purpose only and form no part of the claimed design.
